UNITED STATES PATENT OFFICE

2,403,814

COMPRESSOR

Pietro Maniscalco, Chicago, Ill.

Application February 17, 1942, Serial No. 431,203

5 Claims. (Cl. 230—182)

1

This invention relates to improvements in compressors.

One of the main objects of this invention is to provide an economical and light running compressor, preferably a multistage compressor which comprises a compact cylinder structure including a casing having integral oppositely extending cylinders thereon, and a relatively slender and light running piston unit including a body having integral oppositely extending pistons thereon reciprocable in said cylinders and having inexpensive valves at their ends connected by channels extending directly thru the piston unit.

Another object of this invention is to provide such a compressor which comprises means to produce a cooling effect on the piston unit and the mechanism in the casing, which is preferably done by providing air vents on the casing and means for forcing the air therethru and around the operating members therein.

A more particular object of this invention is to provide in such a multistage compressor a metal piston unit which consists of a slender body having integral at its opposite ends a low-pressure and a high-pressure piston containing each an end socket equipped with a compact, economical valve, and also channels extending directly thru said piston unit from one socket to the other, thus producing a light running and economical piston construction.

Another object of this invention is to provide a highly efficient compressor which is particularly adapted for compressing air, and is also adapted for compressing gaseous refrigerants in air conditioning and refrigerating devices.

These and various other objects and advantages are attained with this invention, as will become apparent from the following description, taken in connection with the accompanying drawings wherein the invention is shown in its preferred form, it being evident that various other arrangements and forms of construction may be resorted to for carrying out the objects and purposes of this invention.

In the drawings:

Fig. 1 is a side elevational view of this invention, with part of the fan-equipped drive wheel broken away.

Fig. 2 is a top plan view thereof, having parts omitted.

Fig. 3 is an enlarged vertical cross-sectional view thereof, taken on line 3—3 of Fig. 1.

Fig. 4 is an enlarged horizontal sectional view, taken on line 4—4 of Fig. 1.

Fig. 5 is a longitudinal vertical sectional view, taken on line 5—5 of Fig. 4.

Fig. 6 is a vertical sectional view taken longitudinally thru this piston unit.

Fig. 7 is a horizontal sectional view thru said unit, taken on line 7—7 of Fig. 6.

Fig. 8 is a vertical cross-sectional view thru said unit, taken on line 8—8 of Fig. 6.

Fig. 9 is an enlarged view of the economical valve construction utilized in this compressor.

This invention is disclosed herein in a preferred form of construction, being illustrated as a multistage compressor which comprises a compact cylinder structure or unit including a casing 10 having a low-pressure or primary cylinder 11 integral on one end and a smaller secondary or high-pressure cylinder 12 integral on the other end, said cylinders extending in opposite directions and being aligned. Cooling fins 13 are preferably also provided on the cylinders. The casing has its upper end open, with a top or cover 14 detachably mounted thereon, and includes a flanged bottom or base 15 for supporting the compressor, said casing being adapted to contain suitable lubricant for lubricating the operating parts.

This compressor further comprises a relatively slender and light running piston unit which includes a body 16 having a low-pressure or primary piston 17 integral on one end and a smaller high-pressure or secondary piston 18 integral on the other end, which are aligned and reciprocable in said cylinders.

The cylinders 11 and 12 are open at their ends and have, respectively, heads 21 and 22 mounted detachably over the end openings, as by flange means 21' and 22' on the heads bolted against the cylinder ends. Said heads 21 and 22 contain, respectively, sockets 23 and 24 having each a valve 25 removably mounted therein; and from the heads 21 and 22 extend, respectively, necks 27 and 28 having conduits or suitable inlet means 29 and outlet means 30 connected thereto, respectively, and providing the fluid inlet and outlet to the compressor.

The piston unit herein is of an easy running construction, and it consists of a unitary metal member which may be economically made in one casting; and, as best shown in Fig. 7, the pistons 17 and 18 are undercut around the body at their inward ends thus providing annular skirt portions 31 and 32 and also plate-like heads 33 and 34 at the outer ends, said heads being provided with sockets 35 and 36 each containing a valve 25 removably mounted therein. Channel means

is provided in this unit, being shown herein as a pair of channels 37 extending directly and substantially straight thru the body and being curved or branched together at their ends 38 to join said sockets 35 and 36, thus extending from one socket to the other and providing communication between the valves therein.

The body 16 is provided with a slot 39, being of substantial length and extending transversely thru it between the channels 37, and cooling fins 40 are preferably also provided around the body. This arrangement thus provides a slender, light running and cool piston unit.

The valves 25 used in this compressor are of a simple and inexpensive construction, preferably consisting of a washer-like member which is threaded or removably mounted in the sockets 35 and 36 of the pistons and 23 and 24 of the cylinders; and this member contains a channel 41 having an enlarged part 42 provided with a flat and smooth valve seat 43 whereon a valve plate 44 is normally held in valve-closed position, by the intermediate parts of a curved wire spring 45 which has its outer parts 46 sprung into a groove 47 cut in the wall surrounding the channel part 42. Said valve member is preferably mounted in the socket by threading it therein, and it is therefore provided with bores or notches 48 adapted to receive the prongs of a suitable tool in applying and detaching this member.

The drive means for reciprocating the pistons in the cylinders comprises a drive shaft 51 which is extended thru the slot 39 in the piston body and is rotatably mounted in a pair of bearing sleeves 52 and 53 seated in a pair of collars 54 and 55 which are mounted in openings 56 and 57 provided in the opposite side walls of the casing, said collars having flange means 54' and 55' thereon which are bolted against the casing, along with suitable sealing means. The collar 55 has a closing plug 58 threaded adjustably in its outer end, which is provided with a pocket 59 in its inner end containing therein a bearing plate 60 and a bearing ball 61 rotary thereon and against which the inner end 62 of shaft 51 bears rotatably. The collar 54 has a flanged closing member 64 bolted to its outer end, thru which the shaft 51 extends, and a coil spring 65 in said collar is confined between an enlarged part 66 on the shaft and an anti-friction bearing 67 positioned at the inner side of member 64, so as to retain the inner end of the shaft in position against ball 61. The shaft herein is preferably actuated by a drive wheel in the form of a pulley-wheel 68 secured on its outer end and driven by a suitable belt or the like.

The driving connections between the shaft and the piston unit, in this form of construction illustrated herein, comprises eccentric means which includes an eccentric 69 detachably fastened onto the shaft to rotate therewith, as by groove and spline means 70 provided on the eccentric and shaft, and a locking bolt 71 threaded in the eccentric and engaging the shaft. Said eccentric is rotatable in a ring portion or hub 72 provided at one end of a crank arm or member 73 which has at its other end an eye portion 74 containing therein a bearing 75, preferably a needle bearing, wherein is mounted a stud or axle-pin 76 which is secured in an aperture provided in the piston body, as by a pin 77 which extends thru suitable holes provided in said stud and in an annular projection 78 on the side of the body.

This compressor is adapted to contain lubricating liquid in the lower part of the casing, and

the ring portion 72 with the eccentric 69 will be effective as splasher means to carry some of the lubricant up and distribute it on the piston body and the inward parts of the cylinders, to lubricate the operating parts in the casing.

This compressor is well adapted for speedily compressing air, and it is likewise adapted for compressing gaseous fluids as are used in the refrigerating industry; and by the slender and light construction of the piston unit this further provides an economical and relatively cool and easy running compressor.

For the purpose of cooling this construction and producing a cool running compressor, the upper part of the casing is furthermore provided with a plurality of air ports or vents thereon; and this is preferably done by providing such vents in the cover 14 which is made dome-shaped, including vents 81 and 82 at the two sides thereof and vent means or slot 83 in its top. Suitable screens 81', 82' and 83' are preferably also mounted across said vents 81, 82 and 83, to avoid entry of undesired matter.

Means is also provided to force the air thru the vents and thru the casing, and this comprises fan means 84 which is conveniently produced by providing fan blades or vanes on the drive wheel 68; so as to force the air into the casing thru vents 81, to flow onto the piston unit and the other parts in the casing, and to pass out thru vents 82 and 83.

In order to better direct the air around the piston unit, I further provide deflecting means 85 in the casing, being preferably in the shape of wing means provided underneath the cover 14 and slanting inwardly, as best shown in Fig. 3; and this wing means is preferably tilted or slanted inwardly to a greater extent at its part 86 near the high-pressure piston, so as to direct the larger portion of the entering air toward said high-pressure end of the piston unit and produce the main cooling effect on it and the high-pressure cylinder, where the pressure and the heat generated thereby is the greatest.

For mounting the piston unit and the drive means in their operative positions in the cylinder structure the valves 25 may be secured in the piston sockets 35 and 36, and the axle-pin 76, with or without the bearing 75 placed thereon, may then be mounted in the piston body, and the piston unit can be inserted thru the open end of the low-pressure cylinder 11, being advanced fully to the head end of the high-pressure cylinder; whereupon the crank member 73 with the eccentric 72 thereon is next inserted thru the open top of the casing, and the eye portion 74 of said member 73, with said bearing 75 therein if that was at first omitted, is next mounted in place on said axle-pin 76. An enlarged notch 87 is provided in the side of the casing, adjacent collar 54 in opening 56, to allow for such mounting of portion 74 on pin 76. The drive shaft can then be inserted thru said opening 56 and extended thru the eccentric, and lock bolt 71 secured in place, whereupon collar 54 with closing member 64 may be mounted in position, and the drive wheel 68 secured on the shaft and the other parts mounted in their proper positions, to provide the operative compressor.

It should be noted that in this invention the piston body 16 is slender and straight and has its longitudinal axis aligned with the axes of the pair of pistons integral on its two ends; also that this body 16 is substantially symmetrical in cross-section and the channel means 37 therein includes

several channels which are placed off-center and extend thru the body from the valve means 25 in one piston end to the valve means 25 in the other providing communication therebetween, while the slot 29, thru which the drive shaft extends transversely of the body, is located between these channels and extends for a substantial length of the body, to lighten the same; and in addition hereto further cooling means is provided, including air vents 81, 82 and 83, and deflecting means 85, together with the air forcing means 84. This compressor construction thus produces a speedily functioning, cool and easy running compressor, providing a substantial improvement over the former ones, including my own either patented or still co-pending.

I claim:

1. In a multistage compressor of the character disclosed and which has a crank casing, alined low and high pressure cylinders at the ends of the casing, low and high pressure pistons operative in said cylinders, a tubular connecting rod between said pistons, and crank means operatively connected to the connecting rod to reciprocate said rod and said pistons as a unit, said pistons having valved passages for controlling passage of fluid between the cylinders and the rod, said rod having heat radiating fins extending outwardly from said rod and movable therewith.

2. In a multistage compressor of the character disclosed and which has a crank casing, alined low and high pressure cylinders at the ends of the casing, low and high pressure pistons operative in said cylinders, a tubular connecting rod between said pistons, and crank means operatively connected to the connecting rod to reciprocate said rod and said pistons as a unit, said pistons having valved passages for controlling passage of fluid between the cylinders and the rod, said rod having heat radiating fins extending outwardly from said rod and movable therewith, said fins extending along the length of said rod between said pistons.

3. In a multistage compressor of the character disclosed and which has a crank casing, alined low and high pressure cylinders at the ends of the casing, low and high pressure pistons operative in said cylinders, a tubular connecting rod between said pistons, and crank means operatively connected to the connecting rod to reciprocate said rod and said pistons as a unit, said pistons having valved passages for controlling passage of fluid between the cylinders and the rod, said rod having heat radiating fins extending outwardly from said rod and movable therewith,

said fins extending along the length of said rod between said pistons, the fins at the low pressure end of said rod extending outwardly from said rod at a greater extent than the fins at the high pressure end of said rod.

4. In a multistage compressor of the character disclosed and which has a crank casing, alined low and high pressure cylinders at the ends of the casing, low and high pressure pistons operative in said cylinders, a tubular connecting rod between said pistons, and crank means operatively connected to the connecting rod to reciprocate said rod and said pistons as a unit, said pistons having valved passages for controlling passage of fluid between the cylinders and the rod, said rod having heat radiating fins extending outwardly from said rod and movable therewith, said fins extending along the length of said rod between said pistons, the fins at the low pressure end of said rod extending outwardly from said rod at a greater extent than the fins at the high pressure end of said rod, the extent of said fins at said low pressure end of said rod being less than the inner radius of the low pressure cylinder for affording entry of said fins into said low pressure cylinder when the low pressure piston reciprocates in said low pressure cylinder, and the extent of said fins at said high pressure end of said rod being less than the inner radius of the high pressure cylinder for affording entry of said latter fins into said high pressure cylinder when the high pressure piston reciprocates in said high pressure cylinder.

5. In a multistage compressor of the character disclosed and which has a crank casing with high and low pressure cylinders and pistons at the ends of the casing and a connecting rod extending through the casing and connected to the pistons, drive means in the casing and crank means operatively connected to the drive means and the connecting rod; a cover mounted on the casing and having air inlet and outlet vents for the passage of air to and from said casing, a deflector attached to said cover and extending downward from the cover and located in spaced relation to and between said inlet and outlet air vents, said connecting rod having heat radiating fins extending outwardly from said rod and movable therewith, said drive means having a shaft extending to the exterior of the casing, a fan on said shaft and located to force air through said inlet vent and against said deflector whereby the air is directed against said fins during the reciprocation thereof.

PIETRO MANISCALCO.
